UNITED STATES PATENT OFFICE.

HENRY DRESES, OF CINCINNATI, OHIO, ASSIGNOR TO THE DRESES MACHINE TOOL COMPANY, OF CINCINNATI, OHIO, A CORPORATION OF OHIO.

RADIAL DRILLING MACHINE.

Application filed January 11, 1923. Serial No. 611,945.

In radial drilling machines the drill-arm is adjustable so as to be located in various radial positions. Such machines usually employ an upright post, about which there is 5 a rotatable column, the drill-arm extending radially from the column and being adjustable up and down on the same. The column is rotatable about the post so as to place the arm in its various radial positions. Clamping 10 means are usually employed for clamping the column with relation to the post when the drill-arm has been positioned.

I have exemplified my invention in connection with a radial drilling machine of 15 this character.

It is the object of my invention to provide new and improved means whereby to clamp the radial drill-arm in selective radial positions; further, to provide clamping 20 means of this character in a drilling machine which are operable by a rotatable power element of the machine; further, to provide control means for the same comprising a manual actuator at the drill-arm; 25 further, to provide clamping means in a drilling machine and control means for the clamping means wherein the control means comprise a cam having a steep angle to afford ready relief in the 30 operating means for the clamp; further, to provide a clamp operating means and control means for the latter so related that the control means yield to undue pressure in the operating means; and, further, to provide clamp operating means in a drilling 35 machine operated by an element in the train of power mechanism for rotating the spindle.

The invention will be further readily understood from the following description and claims, and from the drawings, in which latter:

Fig. 1 is a rear elevation of so much of a drilling machine as is necessary to show 45 my improvements thereon.

Fig. 2 is a front elevation of the same, the post and column being shown in section.

Fig. 3 is a plan view of the gearing at the top of the column.

Fig. 4 is a vertical cross-section taken on 50 the line 4—4 of Fig. 1.

Fig. 5 is a horizontal cross-section taken on the line 5—5 of Fig. 1.

Fig. 6 is a vertical axial section taken on the line 6—6 of Fig. 5. 55

Fig. 7 is a horizontal section taken in the plane of the line 7—7 of Fig. 6.

Fig. 8 is a rear elevation showing the clamping means; and,

Fig. 9 is a plan view detail of the slide- 60 able operating connection.

The drilling machine which I have exemplified comprises a base 21 from which a post 22 extends upwardly, the post being stationary with the base. A rotatable sleeve 65 or column, hereinafter called the rotatable column 23, rotates about the post, guided by bearings 24, 25, between the post and the column. The column is shown as having a split-bearing 26 about the post, the walls 27, 28, of the split 29 in the bearing being drawn toward each other to clamp the bearing about the post, by the clamping means hereinafter described, in order to secure the column in adjusted positions about the post. 75

A drill-arm 31 has a bearing 32 about the outer periphery of the column, and is adjustable to elevation on the column by suitable means, as by screw-rod 33 having threaded connection in a nut 34, secured to 80 the drill-arm, and rotated in suitable manner in either direction for raising or for lowering the drill-arm. When the drill-arm has been adjusted to elevation, it is clamped about the column by means of 85 clamps 35. The drill-arm moves with the column when the latter is rotated for positioning the drill-arm in desirable radial positions about the post.

A drill-slide 38 is adjustable in suitable 90 or desirable manner lengthwise of the drill-arm. A drill-spindle 39 is journaled in the slide in suitable manner, and is rotatable in reverse directions by means of suitable gearing on the drill-slide, the latter gearing 95 being rotated by means of a cross-shaft 40, journaled in bearings 41, 42, on the drill-arm. Interruption may also be effected in the drill-spindle gearing for permitting the drill-spindle to be non-rotative in its bearings. 100

An upright shaft 45 is arranged to drive

the cross-shaft by means of bevel gears 46, 47. The bevel-gear 46 has its hub journaled in a suitable bearing 48 in the drill-arm in usual manner, and has spline-key and groove connection 49 with the upright shaft, so as to transmit the rotations of the upright shaft to the bevel-gear throughout the adjustment to elevation of the drill-arm. The upright shaft is exemplified as journaled in a bearing 50 at its upper end.

In the present exemplification the upright shaft 45 is driven in suitable manner from a prime mover, represented as a pulley 53, on a shaft 54, journaled in bearings 55, in the lower end of the post, and having a bevel-gear 56, secured thereto. The bevel-gear 56 meshes with a bevel-gear 57, fixed to the lower end of an axial shaft 58, journaled in bearings 59, 60, in the post, and having gears 61, 62, secured to its upper end.

Gears 65, 66, are journaled about a stud-shaft 67, fixed in a bearing 68 in the upper plate 69 of the column. The gear 61 meshes with the gear 65. A gear 71 is fixed to the upright shaft 45, and is meshed by the gear 65 for driving the upright shaft.

An arm 73 is swingable by means of a bearing 74, about the upper end of the upright screw-rod 33, this screw-rod having a gear 75 fixed to its upper end. Pinions 76, 77, rotate on the quadrant and are in mesh with each other. The pinion 76 is in mesh with the gear 75. The pinion 77 is arranged to be brought into meshing relation selectively with the gears 62, 66, which rotate in opposite directions, for rotating the upright screw-rod 33 in opposite directions. The shifting of the arm 73 for this purpose is accomplished by suitable means.

The clamp for clamping the drill-arm in radial positions, instanced at the bottom of the column, comprises a bolt 81 journaled in bearings 82, 83, in the walls 27, 28, of the split-bearing 26, and a nut 84 having threaded connection with said bolt. An end-thrust ball-bearing 85 is exemplified between the bearing 82 and the nut. Pressure between the head of the bolt and the nut causes clamping of the column about the post for holding the radial drill-arm in radial positions. The bolt is rotatable in its bearings so as to control the directions in which an arm 87, shown integral with the nut, extends radially of the axis of the bolt, when the arm is in clamped relation and in unclamped relation. When the bolt has been thus adjusted, a set-screw 88 fixes the bolt in adjusted position.

A tension bolt 91 is journaled in the walls 27, 28, and has an adjusting nut 92 and a lock-nut 93 thereon, for fixing the distance between the adjusting nut and the head of this tension-bolt, to limit the amount

of separation between the walls 27, 28, 65 when the clamp-screw is released.

I provide means for operating the clamp by an operative element in the drilling machine, this operative element being exemplified as the upright shaft 45, which is one of 70 the rotatable elements for rotating the drill-spindle. A pair of gears 95, 96, is fixed to this upright shaft.

A box 98 has a bearing 99 therein, in which the lower end of the upright shaft is journaled, the box being provided with a lug 100, by means of which it is secured by bolts 101 to a boss 102 at the lower end of the column, so as to rotate with the column.

A shaft 105 is journaled in the box. 75 Gears 106, 107, rotate in reverse directions about this shaft. The gear 106 meshes with the gear 95. The gear 107 meshes with a pinion 108, rotatable on a stud 109 in the gear-box, the pinion 108 meshing with the 80 gear 96. These trains of gearing rotate the gears 106, 107, in opposite directions.

A clutch-collar 111 is secured to the shaft 105 by means of a pin 112. A clutch 113 is located between the gear 106 and the 90 clutch-collar, and the clutch 114 is located between the gear 107 and the clutch-collar. These respective clutches are exemplified as friction clutches comprising fibre friction-disks arranged so that end pressure thereon 95 respectively by the clutch-collar causes driving relation through either clutch between the respective gears 106, 107, and the shaft 105.

Separating pins 116, the ends of which 100 engage washers 117, 118, between the respective ends of the pins and the gears 106, 107, maintain said gears in proper separated relation for proper operation of the clutches. The gears 106, 107, are held toward each 105 other by the bearings 119, 120, in the gear-box. The bearing 120 is exemplified as in a releasable block 121, forming part of the gear-box.

A ball-bearing 122 surrounds the reduced 110 end 123 of the shaft 105, between a washer 124 engaging a shoulder 125 on said shaft, and a collar 126 pinned to said reduced end by a pin 127. The bearing 122 is located in the bearing 119. A bearing 131 is received about the reduced end 123 of the shaft 105, between a washer 133 engaging a shoulder 134 on said shaft, and a sleeve 135, secured to said reduced end by a pin 136. The bearing 131 is received in the bearing 120.

A screw-rod 141 is rotated by the shaft 105, exemplified as accomplished by a spline-key and groove connection 142, between the screw-rod and the sleeve 135, for causing 125 rotation of the screw-rod with said shaft, but permitting endwise movement of said shaft for operation of the clutches, in order

to impart rotation in reverse directions to said shaft.

The screw-rod is held endwise as by a collar 144, fixed thereto by a pin 145, and ball-bearings 146, 147, at the respective ends of said collar. The collar and ball-bearings are located in a cap 148, and they are held against endwise movement between a collar 149 clamped between the cap and the block 121, and a flange 150 of the cap. The cap and block are fixed to the box by means of bolts 151.

A nut 153 is threaded about the screw-rod 141, and is arranged to be raised and lowered by rotation of the screw-rod in opposite directions. The nut 153 has connection with the arm 87, exemplified as accomplished by providing the arm with a fork 154, the tines of which are at the respective sides of the nut engaged by shoulders 155, 156, shaped so as to permit axial movement of the nut and arcuate movement of the arm.

The operating means for the clamp just described, are controlled by suitable control means, exemplified as comprising a lever 161, pivoted by means of links 162 to the gear-box, the links being articulated by pins 163 to the cover 164 of the gear-box, and by means of pins 165 to the lever. The cover 30 of the gear-box is secured to the body of the box by means of bolts 166.

A collar 168 is fixed to the shaft 105 by means of a pin 169. Ball-bearings 170, 171, are at the respective ends of the collar, and have ball and socket connection 172 with the lever, part of the socket whereof is in the body of the lever, and part in a cap 173 fixed to the lever proper by screws 174.

The operation of the lever is shown effected by a cam 176, exemplified in a cam-collar 177, fixed to a rock-shaft 178 by a set-screw 179. The rock-shaft is journaled in a bearing 180 in the cover 164 and a bearing 181 in the top-plate 69 of the column. This shaft shifts with the column and drill-arm. The lever 161 is provided with a pin 182, on which there is a roller 183, engaged by the cam.

The cam is shown as a cam-slot, the walls 50 of which engage the roller respectively during opposite directions of rotation of the cam. Movement of the cam in one direction causes engagement of the clutch 113 for rotating the screw-rod 141 in one direction, represented as a clamping direction, effected by upward movement of the arm 87, and movement of the cam in the opposite direction causes engagement of the clutch 114, for rotation of the screw-rod in the opposite direction, for effecting unclamping of the clamp.

The angle of the control-cam 176 is preferably steep so as to limit the force exertible by the control-cam upon the friction 65 clutches, in order to limit the force of fric-

tion contact in the friction clutches within the safety requirements for said operating means for closing and opening said clamp.

Manual operating means are provided for the cam, exemplified as a rock-shaft 185 journalled in bearings 186, 187, on the drill-arm, and having a bevel-gear 188 fixed thereto, which meshes with a bevel-gear 189 having spline-key and groove connection 184 with the rock shaft 178. A handle-bar 191 has a handle 192 thereon, extending to the front of the machine, preferably within convenient reach of the operator while operating the machine, and exemplified as moving with the drill-slide. 80

The handle-bar has articulation 194 with an arm 195, which has a bearing 196 about the rock-shaft 185. This bearing has spline-key and groove connection 197 with said rock-shaft, so as to rock said rock-shaft with 85 the movements of said arm and handle-bar. The bearing 196 is provided with an annular groove 198, into which a lip 199 of a clip 200 is received, the clip being fixed to a bearing 201 on the spindle-slide, so as to 90 cause the bearing 201 and the bearing 196 to move together with the spindle-slide.

An arm 204 is pivoted on a pin 205 in a bearing 206 fixed to the front of the spindle-slide, this arm having articulation 207 with the handle-bar to properly position the handle of the latter with relation to the drill-arm. An end-limit ball-bearing 211 is held to the screw-rod 141 by a collar 212, secured to said screw by a pin 213, and a sleeve 214, having its ends flanged as at 215 and 216 respectively about the ball-bearing 211, and the collar 212. 100

Rearward movement of the handle-bar will cause engagement of one of the clutches and forward movement of the handle-bar will cause engagement of the other of the clutches. 105

The weight of the handle-bar and its arms is preferably such that it will move the cam 176 into an intermediate position with relation to the pin 182 on the lever 161, so as to place the clutches 113, 114, in neutral positions. 110

The resistance to operation in the clutches, aided by the steep angle of the cam 176, makes continued application of control force at the handle 192 necessary to cause continuation of rotation of the screw rod 141 in either direction. When the split-bearing 26 has been fully clamped, or the nut 153 strikes the end-limit stop 211, slippage will take place in the respective clutches to prevent injury or damage, and the resultant extra resistance will be felt by the operator at the handle 192, who will thereupon release the handle. Upon release of the handle, the cam 176 will move to intermediate or neutral position for releasing the clutches. 115 120 125 130

In operation, if it is desired to change the radial position of the drill-arm, and it being assumed that the clamp is in clamped position, the handle-bar is moved in one direction, for instance, rearwardly, for raising the lever 161 and the shaft 105 for engaging the clutch 113, thereby rotating the screw 141 to cause descent of the nut 156 and unclamping of the clamp.

Continued exertion on the handle-bar in the given direction is necessary to continue the unclamping movement of the clamp-arm. If the operator should continue to exert force upon the handle-bar in said given direction after the nut strikes the end-limit ball-bearing 216, the resistance to further rotation of the screw, by having the nut reach its end-limit of movement, will cause slippage in the friction-clutch 113, due to the fact that, owing to the great inclination of the cam 176, sufficient force can not be exerted by the handle-bar to prevent such slippage.

Such additional force will also be communicated by means of the cam to the handle-bar to advise the operator that the unclamping limit of movement has been reached, whereupon the operator will place the handle-bar in neutral position, or the handle-bar will, in the present instance, drop to neutral position upon its release by the operator.

The adjustment of radial position of the drill-arm having been made, the operator will move the handle-bar in the opposite direction, in this instance, by pulling on the handle-bar, which, by reason of the position of the handle-bar at the drill-spindle, can be done while the operator is viewing the position of the drill point with relation to the work for accurate radial position of the drill-arm. This opposite movement of the handle-bar will cause opposite movement of the nut 153 and the clamp-arm for instance to the position shown in the drawings, for clamping the clamp.

When the clamping has been effected, the resistance to further movement of the nut will cause slippage in the opposite clutch 114, the resistance being communicated to the cam and to the operator through the handle-bar. The operator will thereupon return the handle-bar to neutral position, or the handle-bar will, upon its release, drop to neutral position for again placing the clutches in neutral position.

The angle of the cam is such that the operator cannot exert sufficient pressure through it upon the clutch 114 to detrimentally affect the operating parts of the clamp.

Having thus fully described my invention, what I claim as new, and desire to secure by Letters Patent, is:

1. In a radial drilling machine, the com-

bination of an upright post, an upright column rotatable about said post, a radial drill-arm, power means for adjusting said drill-arm to elevation on said column, a drill-spindle on said drill-arm, power means for rotating said drill-spindle, clamping means for clamping said column with relation to said post, operating means for said clamping means having power connection with said last-named power means, and manual control means for said operating means mounted on and movable with said drill-arm.

2. In a radial drilling machine, the combination of an upright post, a column, a drill-arm on said column, said column rotatable about said post for radial positions of said drill-arm, a drill-spindle on said drill-arm, a clamp comprising a rockable member, operating means for said clamp comprising complementary threaded members including a rotatable threaded member, a shaft with which said rotatable threaded member has connection, reversely rotating gears, clutching means for clutching either of said reversely rotating gears to said shaft, and manual control means having operative connection with said clutching means.

3. In a radial drilling machine, the combination of an upright post, a column, a drill-arm on said column, said column rotatable about said post for radial positions of said drill-arm, a drill-spindle on said drill-arm, a clamp comprising a rockable member, operating means for said clamp comprising complementary threaded members including a rotatable threaded member, a shaft with which said rotatable threaded member has connection, reversely rotating gears, clutching means for clutching either of said reversely rotating gears to said shaft, and means for operating said clutching means comprising a cam of less power by manual movement than said operating means having operative connection with said shaft for axial movement of said shaft, and a manual operating part at said drill-arm for said cam.

4. In a radial drilling machine, the combination of an upright post, a column, a drill-arm on said column, said column rotatable about said post for radial positions of said drill-arm, a drill-spindle on said drill-arm, a clamp for clamping said column with relation to said post, operating means for opening and closing said clamp comprising an operated power member of said drilling machine and opposed friction clutches, and control means for said operating means comprising a cam and a manual actuator for said cam, the angle of said cam being such as to limit the force of friction contact in said friction clutches within the safety requirements for the said

operating means for closing and opening said clamp.

5. In a radial drilling machine, the combination of an upright post, a column, a 5 drill-arm on said column, said column rotatable about said post for radial positions of said drill-arm, a drill-spindle on said drill-arm, a clamp for clamping said column with relation to said post, operating 10 means for said clamp comprising an operated power member of said drilling machine and opposed friction clutches, control means for said operating means comprising a cam, a manual actuator for said cam, 15 and means to normally move said manual actuator into neutral position.

6. In a radial drilling machine, the combination of an upright post, a column, a 20 drill-arm on said column, said column rotatable about said post for radial positions of said drill-arm, a drill-spindle on said drill-arm, a clamp for clamping said column with relation to said post, a screw-rod for operating said clamp, a shaft, a 25 connection between said shaft and said screw-rod for causing combined rotations of said shaft and said screw-rod and permitting axial movement of said shaft with relation to said screw-rod, a pair of oppositely rotating gears about said shaft, a clutch-collar movable with said shaft, 30 clutches between said clutch-collar and said respective gears, and control means having connection with said shaft for operating said 35 clutches.

7. In a radial drilling machine, the combination of an upright post, a column, a radial drill-arm on said column, said column rotatable about said post for radial 40 positions of said drill-arm, a drill-spindle on said drill-arm, a clamp for clamping said column with relation to said post, a screw-rod, a nut thereabout for operating said clamp, a shaft, a connection between 45 said shaft and said screw-rod for causing combined rotations of said shaft and said screw-rod and permitting axial movement of said shaft with relation to said screw-rod, means limiting endwise movement of 50 said nut on said screw-rod, oppositely rotated gearings for rotating said shaft selectively in opposite directions, and means controlling the latter by axial movement of said shaft, including a cam, and an operating arm for said cam normally movable 55 into neutral position by gravity.

8. In a radial drilling machine, the combination of an upright post, a column, a 60 drill-arm on said column, said column rotatable about said post for radial positions of said drill-arm, a spindle-slide on said drill-arm, a drill-spindle on said spindle-slide, a clamp for clamping said column with relation to said post, a screw-rod, a nut 65 thereabout for operating said clamp, a shaft,

a connection between said shaft and said screw-rod for causing combined rotations of said shaft and said screw-rod and permitting axial movement of said shaft with relation to said screw-rod, a pair of oppositely rotating gears about said shaft, a clutch-collar movable with said shaft, clutches between said clutch-collar and said respective gears, and control means having operative connection with said shaft and arranged for axial 70 movements of said shaft for actuation of said respective clutches, said control means comprising a manual actuator on said drill-arm, and connection between said actuator and said spindle-slide for causing movement 75 of said manual actuator lengthwise of said drill-arm with said spindle-slide.

9. In a radial drilling machine, the combination of an upright post, a column rotatable thereabout, a split-bearing at the base 80 of said column about said post, a clamp for said split-bearing, a drill-arm extending laterally from said column, said column and drill-arm adjustable to radial positions about said post, means for operating said clamp 85 comprising a gear-box at the base of said column containing reversely rotating gears, and clutch-mechanism to selectively connect said gears with said clamp, and manual 90 means at the drill-arm for operating said 95 clutches.

10. In a radial drilling machine, the combination of an upright post, a column rotatable thereabout, a split-bearing at the base of said column about said post, a clamp 100 for said split-bearing, a drill-arm extending laterally from said column, said column and drill-arm adjustable to radial positions about said post, means for operating said clamp comprising a gear-box at the base of said 105 column containing reversely rotating gears and clutch-mechanism to selectively connect said gears with said clamp, a lever at the outside of said gear-box for operating said 110 clutches, a cam on said gear-box for operating said lever, and manual control means at said arm having connection with said cam.

11. In a radial drilling machine, the combination of a radial drill-arm, a clamp to 115 clamp said drill-arm in radial positions, an actuating arm therefor, a nut having operative connection with said arm, a screw-rod for said nut, oppositely rotating gearings for rotating said screw-rod, means for operatively connecting said respective gearings with said screw-rod for respective opposite rotations of the latter, and control means for the latter comprising a manual actuator.

12. In a radial drilling machine, the combination of a radial drill-arm, a clamp to 125 clamp said drill-arm in radial positions, an arm therefor, a nut having operative connection with said arm, a screw-rod in said nut, means for positioning said screw-rod end- 130

wise, a shaft, connection between said shaft and said screw-rod for combined rotations of said shaft and said screw-rod and for axial movement of said shaft with relation to said screw-rod, oppositely rotatable gears about said shaft, a clutch-collar fast to said shaft between said gears, clutches between said clutch-collar and said respective gears, a

lever for axially moving said shaft, and manual control means for the latter comprising a cam having operative connection with said lever.

In testimony whereof, I have hereunto signed my name.

HENRY DRESES.
